UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF DELAWARE.

TOY GUN.

Application filed February 16, 1924. Serial No. 693,196.

To all whom it may concern:

Be it known that I, WILLIAM F. SCHMIDT, citizen of the United States, residing at Wyandotte, county of Wayne, State of Michigan, have invented a certain new and useful Improvement in Toy Guns, and declare the following to be a full, clear, and exact description of the same, such as will enable others skilled in the art to which it pertains to make and use the same, reference being had to the accompanying drawings, which form a part of this specification.

My invention relates to toy guns and objects of my improvements are to provide an apparatus that is efficient, cheap to construct, and assemble, and that affords accessibility, as more specifically pointed out hereinafter.

I secured this object in the device illustrated in the accompanying drawing in which:—

Figure 1 is a side view of a toy gun embodying my invention.

Fig. 2 is a vertical section through the axis of part of the barrel of the gun.

Fig. 3 is the inverted plan view of Fig. 2.

Fig. 4 is a section on the line IV, IV, Fig. 2.

Fig. 5 is a perspective view of the thimble forming a partition and the connecting means between the main and auxiliary barrel.

Fig. 6 is a plan view of a gun embodying my invention, taken apart to economize room in transportation and packing.

Fig. 7 is a section similar to Fig. 2, to an enlarged scale showing a modified construction.

Fig. 8 is a section on the line VIII, VIII, Fig. 7.

Fig. 9 is a view of the formed sheet from which the shell of the thimble, Fig. 7, is rolled.

Fig. 10 is a plan view of the thimble of Fig. 7.

a is the main barrel and *a*² is the stock. *b* is a piston which, in the kind of gun contemplated, is thrown forward by a spring *b*² to compress the air in front of it, and thereby to give the impulse to the projectile.

In the so called popgun, the projectile is of cork lightly inserted in the muzzle of the barrel *a*, which cork is thrown forward,

as the projectile, when the piston *b* compresses the air between it and said cork.

My invention enables one to cheaply and readily transform such popgun to an effective air rifle, which is readily accessible for the purposes hereinafter pointed out.

d is a thimble stamped out of sheet-metal open at one end and closed at the other end, except for the inwardly projecting, axial, tubular portion *d*³. *d*⁴ is a lug extending radially outward from the peripheral wall of the thimble. The thimble *b* is placed in the muzzle of the barrel *a* with its closed inner end inward and forming a partition *d*² across the bore of said barrel. Said thimble is then spot-welded in position.

c is the auxiliary barrel consisting of an outer cylindrical casing, or false barrel, *c*², of the same diameter as the main barrel *a*, and a co-axial small central barrel *f*. The barrel *f* is held in position by a partition *f*² at the muzzle of the barrel *c*, and a second partition, *f*³, extending across the interior of the false barrel, or outer casing, *c*², at a distance from the partition, *f*². *c*³, (Fig. 3), is an L-shaped slot cut into the wall of the false barrel *c*² extending inward from its inner end and then at right angles. The false barrel, *c*², is shoved over the protruding end of the thimble *d*, the lug *d*⁴ passing into the slot *c*³, and is then turned about its axis so that the lug *d*⁴ shall be engaged in the lateral extension of said slot, as shown in Fig. 3, thus forming a bayonet joint holding the auxiliary barrel in place.

e is a felt washer fitting within the bore of the thimble *d*, cut away at its center to pass around, and fit closely against the outer wall of the projection *d*³, and lying against the inner wall of the closed inner end, or partition *d*², of said thimble. *e*² is an annular washer fitting within the barrel *a*, and lying against the closed end of partition *d*² of the thimble *d*.

When the auxiliary barrel *c* is adjusted to position as above described, the inner barrel *f* is caused to pass over the tubular projection *d*³ with a close fit, and engage against the washer *e*, to form a tight joint.

Now if a shot *m* of the diameter of the bore of the barrel *f* is placed in said barrel and allowed to fall to the inner end thereof, when it gets to the slight contraction of the bore of said barrel caused by the projection

d^3 , it will be stopped and held in this position by friction. If now the piston b is thrown forward by the spring b^2 it will compress the air in front of it, and thereby 5 propel the shot m through the barrel f and project the same from the muzzle of the barrel.

In toy air rifles of this kind, the shot m sometimes becomes lodged in the position 10 shown, so that it cannot be thrown out by the action of the air in front of the piston. By the above construction, the auxiliary barrel c may be readily removed and a small rod or ramrod used to dislodge the 15 shot m .

The piston b requires occasional oiling to keep it tight and in good working order. In the above construction it is easily accessible for this purpose by removing the auxiliary barrel, as above described, and oiling the piston through the tubular projection d^3 .

By the above construction, economy of 25 space in packing for transportation is also secured. The auxiliary barrel c may be removed or placed in the box or receptacle x beside the rest of the gun, as illustrated in Figure 6, so that a shorter receptacle may be employed.

Instead of forming the thimble d by pressing the same out of a single sheet, it may be 30 constructed as illustrated in Figures 7 to 10 inclusive, in which the shell ba is rolled from a blank dx , (Fig. 9), into one edge of which is cut the slot dx^4 , and the opposite edge being cut away, as indicated at dx^5 . This sheet is then rolled to a cylindrical 35 form, bringing the two edges, dx^2 and dx^3 , together, as shown in Figure 10. The cut-away portion, dx^5 , then forms an entrance 40 passage to the L-shaped slot, and the cut-away portion, dx^4 , forming the laterally extending portion of said slot.

The inner end of the cylinder da is closed 45 by the cut portion, d^2a , fitting and secured in its end.

The engaging lug is formed by cutting out 50 a portion of the metal of the cylinder c^2 , and turning the same radially inward to form the lug ca . This lug enters and engages in the L slot above described in the usual way.

What I claim is:

1. The combination of a barrel, a thimble fixed in said barrel so that its end shall form a stationary abutment, said thimble having one end closed with an aperture in said closure having its walls extended to form a tubular extension therefrom for the purpose described.
2. The combination of a barrel, a thimble fixed in said barrel so that its end shall form a stationary abutment, said thimble having one end closed with an aperture in said clo-

sure having its walls extended to form a tubular inwardly projecting extension therefrom for the purpose described. 65

3. In an apparatus of the kind described, a main barrel, a fixed partition in said barrel provided with an axially extending tubular portion and an auxiliary barrel adapted to be removably secured to said main barrel and form an extension thereof, said auxiliary barrel having a bore with walls engaging the walls of said tubular portion with a tight joint. 70

4. In an apparatus of the kind described, a main barrel, a fixed partition in said barrel provided with an axially extending tubular portion and an auxiliary barrel adapted to be removably secured to said main barrel and form an extension thereof, said auxiliary barrel having a bore with walls engaging the walls of said tubular portion with a tight joint, said tubular portion projecting into said bore. 75

5. In an apparatus of the kind described, the combination of a main barrel and an auxiliary barrel, a thimble extending into said main barrel and fixedly secured therein so as to have a part projecting therefrom, said auxiliary barrel fitting over and engaging the protruding portion of said thimble to form an extension of said main barrel and to secure said auxiliary barrel in position, said thimble being closed at its inner end except for an aperture therein for the purpose described, said aperture having walls forming a tubular extension, engaging the walls of the bore of said auxiliary barrel. 80

6. In an apparatus of the kind described, the combination of a main barrel and an auxiliary barrel, a thimble extending into said main barrel and secured therein so as to have a part projecting therefrom, said auxiliary barrel fitting over said thimble to form an extension of said main barrel, said thimble being closed at its inner end except for an aperture therein for the purpose described, said aperture having walls forming a tubular extension, engaging the walls of the bore of said auxiliary barrel and extending into the same. 100

7. In an apparatus of the kind described, a thimble formed of a circular sheet having the slot dx^4 in one edge, and the cut-away portion dx^5 in the other edge, the same being shaped to form the L slot and rolled into a cylindrical form. 105

8. In combination with the device of claim No. 7, a cylinder c^2 cut away and bent inward to form a lug ca to engage in the L slot. 110

In testimony whereof, I sign this specification.

WILLIAM F. SCHMIDT.
